(57) **CLAIM**

The ornamental design for a radiotherapy pendant, as shown and described.

DESCRIPTION

FIG. 1 is a perspective view of a pendant, in accordance with a first embodiment.

FIG. 2 is a front view of the pendant, in accordance with the first embodiment.

FIG. 3 is a back view of the pendant, in accordance with the first embodiment.

FIG. 4 is a right side elevational view of the pendant, in accordance with the first embodiment.

FIG. 5 is a left side elevational view of the pendant, in accordance with the first embodiment.

FIG. 6 is a bottom view of the pendant, in accordance with the first embodiment.

FIG. 7 is a top view of the pendant, in accordance with the first embodiment.

FIG. 8 is a perspective view of a pendant, in accordance with a second embodiment.

FIG. 9 is a front view of the pendant, in accordance with the second embodiment.

FIG. 10 is a back view of the pendant, in accordance with the second embodiment.

FIG. 11 is a right side elevational view of the pendant, in accordance with the second embodiment.

FIG. 12 is a left side elevational view of the pendant, in accordance with the second embodiment.

FIG. 13 is a bottom view of the pendant, in accordance with the second embodiment.

FIG. 14 is a top view of the pendant, in accordance with the second embodiment.

FIG. 15 is a perspective view of a pendant, in accordance with a third embodiment.

FIG. 16 is a front view of the pendant, in accordance with the third embodiment.

FIG. 17 is a back view of the pendant, in accordance with the third embodiment.

(Continued)

FIG. 18 is a right side elevational view of the pendant, in accordance with the third embodiment.

FIG. 19 is a left side elevational view of the pendant, in accordance with the third embodiment.

FIG. 20 is a bottom view of the pendant, in accordance with the third embodiment; and,

FIG. 21 is a top view of the pendant, in accordance with the third embodiment.

The claimed radiotherapy pendant is not intended to be limited to the scale illustrated in the figures. The broken-line text illustrates unclaimed environment and forms no part of the claimed design. The surface shading lines illustrated in the drawings are provided only to indicate the contour or curvature of the surfaces. They do not indicate color, texture, or markings that actually exist thereon, or indicia, graphic representations, surface treatment, or any other ornamentation applied to the article.
